UNITED STATES PATENT OFFICE.

MICHAEL REINSTEIN, OF LONDON, ENGLAND.

WASHABLE BRUSH.

1,031,586.

Specification of Letters Patent.

Patented July 2, 1912.

Application filed January 17, 1912. Serial No. 671,739.

To all whom it may concern:

Be it known that I, MICHAEL REINSTEIN, of 18 Denmark street, Charing Cross Road, in the parish of St. Giles, in the county of 5 Middlesex, London, W. C., England, hairdresser, have invented a new and useful Improvement in Washable Brushes, of which the following is a specification.

This invention relates to washable brushes, 10 such as lather and all kinds of brushes where perfect sanitation is absolutely necessary and has for its object to provide an improved and convenient arrangement whereby after lathering, or using it for any other purpose, 15 the brush in its entirety can, before being used again be unrolled and then cleansed by washing by hand or machinery process and boiled then dried and ironed or mangled like an ordinary pocket handkerchief, so 20 destroying all bacteria and accumulations of matter which are usually found in the sockets of ordinary shaving brushes after continual use; thus cleansed the article is rolled up and is again ready for use; rolled 25 up it can be used as a brush; unrolled it can be used as a washing square, pad or washing-glove.

Brushes are known constructed by rolling up strips formed by weaving bristles 30 together by a warp extending across a portion of their length, the whole being firmly fixed in a handle; and brushes are also known in which tufts of bristles are secured to a strip of canvas which is coiled up to 35 form the brush, so that it can be uncoiled for thorough washing or other cleansing.

Describing now a brush constructed according to my invention; Figure 1 of the drawings herewith is a portion of the brush 40 illustrating the manner in which a tuft or strand of real or imitation hair bristle or fiber marked A is plaited, braided or interlaced with 2 or more strong threads of washable material marked B. As each tuft or strand is so plaited, braided or interlaced 45 a thin twine or thread of washable material marked C is then looped around the head of each tuft or strand in order to secure and prevent them from becoming loose, as illustrated in Fig. 2 of the drawings.

Fig. 3 is a section of the brush showing 50 by the above means a number of the tufts or strands in the complete stage made into

a strip of any required length. Such required length is then affixed for instance by 55 sewing on to one or more edges of a strip or square of any kind of washable material or it can be sewed or otherwise affixed along one or more edges between 2 square pieces of toweling or such like material one edge of 60 the square being left unfastened.

Fig. 4 of the drawings gives an illustration of the tufts or strands A sewed on to the edge of the square or piece of washable material B. Such square or piece can then be 65 folded by placing together the points D to C and rolled from left to right or vice versa thus forming a brush for lathering or other purposes. The brush as above described can be used if so desired in a shell or case 70 of metal for a handle.

What I claim as my invention and desire to secure by Letters Patent, is:—

1. In a brush, a bunch of bristles returned upon itself having its intermediate portion 75 pressed inwardly for a short distance between the folds of the bunch of bristles to provide a plurality of spaced and substantially parallel portions, a plurality of strands interwoven about the parallel portions of said bunch of 80 bristles, and a binding strand looped at spaced intervals about said first-named strands and being arched over said parallel portions between the loops.

2. A brush comprising a plurality of 85 bunches of bristles, each of which is returned upon itself and having its intermediate portion pressed inwardly for a short distance between the folds of the bunch of bristles, a plurality of strands interwoven about the intermediate pressed-in 90 portions of each of said plurality of bunches of bristles, a binding strand looped at spaced intervals about said first-named strands and being arched over said intermediate pressed-in 95 portions between the loops, and a strip of flexible material having one edge thereof secured to the folded portion of the bunches of bristles, substantially as described.

In witness whereof I have hereunto set 100 my hand in the presence of two witnesses.

MICHAEL REINSTEIN.
